UNITED STATES PATENT OFFICE.

CORNELIUS WEYGANDT GARIS, OF EASTON, PENNSYLVANIA.

NON-REFILLABLE BOTTLE.

SPECIFICATION forming part of Letters Patent No. 596,205, dated December 28, 1897.

Application filed March 1, 1897. Serial No. 625,586. (No model.)

To all whom it may concern:

Be it known that I, CORNELIUS WEYGANDT GARIS, a citizen of the United States, residing at Easton, in the county of Northampton and 5 State of Pennsylvania, have invented certain new and useful Improvements in Non-Refillable Bottles; and I do declare the following to be a full, clear, and exact description of the invention, such as will enable others skilled 10 in the art to which it appertains to make and use the same.

My invention relates to a non-refillable bottle; and the object is to provide a device of this character which cannot be refilled and sold as an original package without detection; furthermore, to provide the bottle with a glass-cutter by means of which a portion of the neck may be removed for the purpose of gaining access to the contents, and, finally, 20 to provide a non-refillable bottle which shall be simple of construction and comparatively inexpensive of production.

With these objects in view the invention consists of certain features of construction 25 and combination of parts, which will be hereinafter fully described and claimed.

In the accompanying drawings, Figure 1 is a perspective view of a bottle embodying my invention. Fig. 2 is a longitudinal vertical 30 sectional view through the same, and Fig. 3 is a detail perspective view of the locking-bolt and its actuating-spring. Fig. 4 is a perspective view of the glass-cutting device.

In the drawings, 1 denotes a bottle, jar, or 35 other vessel the interior wall of the neck of which is provided with an annular groove 2, below which is adapted to be driven the upper end of a cork 3.

4 denotes the seal, which is preferably made 40 of metal, porcelain, or analogous impenetrable material and which is provided in its lower end with a recess 5, intersected by two transverse holes 6.

7 denotes a pintle which extends across the 45 recess.

8 denotes the bolts, which are seated in the transverse holes 6 and are provided with eyes in their inner ends, through which project the arms of a coiled spring 9, the coil 10 of 50 which embraces the pintle.

After the bottle has been filled the cork is

driven into the neck below the annular groove therein, and the seal is then inserted in the neck until its bolts arrive opposite the groove, when they will spring outward and lock the 55 seal in place against removal.

To remove the contents of the bottle, the neck above the seal must be removed. A common practice now existing is to break the neck on the lines of the groove; but this is 60 found objectionable, for the reason that in doing so very often the entire bottle is broken and the contents lost. To overcome this objection, I have provided the glass-cutter, which is connected to the bottle in a novel 65 manner and by means of which a portion of the neck of the bottle will be severed without the liability of breaking the bottle. This glass-cutter consists of a block 11, preferably triangular in shape, having journaled in one of 70 its corners a cutter-wheel 12, while one side of the block is formed with a groove or grooves 13. A wire or band is encircled about the bottle-neck and lies in the groove or grooves and clamps the block with its cutter into firm 75 engagement with the bottle-neck.

When it is desired to open the bottle, all that is necessary is to press the thumb firmly against the block and force it around the bottle-neck, thus cutting the glass and allowing 80 the upper portion of the neck to be removed without damaging the remaining portion of the bottle.

Having thus described my invention, what I claim, and desire to secure by Letters Patent, is—

The combination with a bottle or vessel of an immovable and impenetrable seal to close its outlet end, of a triangular block having a cutter secured thereto and provided with 90 grooves, and a wire wound around the neck of said bottle and in the grooves in the triangular block and serving to clamp the block to the vessel and permit of its circular motion about the same, substantially as set forth. 95

In testimony whereof I hereunto affix my signature in presence of two witnesses.

CORNELIUS WEYGANDT GARIS.
